MERL R. WOLFARD, OF CAMBRIDGE, MASSACHUSETTS.

ATOMIZING-NOZZLE.

1,342,486.

Specification of Letters Patent. Patented June 8, 1920.

Application filed August 11, 1916. Serial No. 114,464.

To all whom it may concern:

Be it known that I, MERL R. WOLFARD, a citizen of the United States, residing at Cambridge, in the county of Middlesex and 5 State of Massachusetts, have invented new and useful Improvements in Atomizing-Nozzles, of which the following is a specification.

This invention relates to improvements in 10 combined nozzles and valves, particularly such as are suitable for use in internal combustion engines. It relates especially to apparatus for intermittently projecting a stream of liquid fuel in atomized form. It 15 is an object of the invention to provide for automatically cutting off the stream sharply upon cessation of the pressure which is causing the projection. It is a further object to provide a nozzle which will positively and 20 effectively distribute the fuel charge under severe conditions of temperature and pressure, as for example, in a place where the temperature may rise above 1000° Fahrenheit, and the pressure to 400 pounds per 25 square inch or more, as within the combustion chamber of an engine, while combustion is in progress. One situation in which such a nozzle may be used is illustrated in my pending application for Patent Serial 30 No. 85,758, wherein the structure of the present drawing is disclosed but not claimed. Reference is also made to my pending application for Patent Serial No. 8830 wherein is shown and claimed a combined nozzle 35 and valve embodying some features of the structure which is herein shown. Overcoming certain difficulties hitherto found with apparatus of this sort, it is the object of the present invention to provide for successful predetermination of the direction in 40 which it will throw its spray, usually in all directions from the axis, without liability to become clogged on one side or another by impurities in the oil or by carbon deposits 45 resulting from heat or other causes; and in general to provide the other advantages that are characteristic of the invention herein disclosed. One result is that liquid fuel can by a safe and simple plunger pump be 50 broken into fine particles and made to pervade the body of air surrounding or moving past its place of discharge. The invention may be embodied in various forms, differing in sundry respects from the particu-

lar embodiment which is here shown to 55 illustrate the invention. It is intended by this patent to cover by suitable expression in the appended claims whatever features of patentable novelty exist in the invention disclosed. Important features of the structure here disclosed include the provision of 60 means for conducting the oil to a place near the point of discharge through a relatively large or main conduit, by which is meant a conduit large enough in cross section to be 65 free from clogging, and the provision of distributing passages leading from this main conduit which are both short and relatively much smaller than the main conduit, as for example, having a cross section of 70 only five per cent. or ten per cent. as large. This makes very short the distance in which carbon might lodge; it reduces the tendency of carbon to be formed, as compared with a long small passage, in proximity to high 75 temperatures; and it makes for automatic clearing, for the reason that if one of the passages should become clogged the force needed to expel the charge through the remaining passages would be materially increased, and this would tend strongly to free the clogged one. In the preferred form of 80 the invention each distributing passage is essentially only a hole through a thin wall, directly into what may be termed a distributing cavity which permits the oil to escape around more or less of the periphery of the nozzle whenever the nozzle valve is forced from its seat, as hereinafter more 85 fully set forth. A minute groove leads from each of these distributing cavities across the seat to the discharging edge of the nozzle. This prevents the leaving of a residual drop of oil at the edge of the valve after each 90 stroke, for the flow of oil becomes concentrated in the grooves, as the valve closes, and so long as it continues at all it proceeds with such an enhanced velocity that the skin 95 tension is overcome and the particles do not cling to the edge of the nozzle, even during the last part of the stroke, when the flow is relatively small. In the accompanying drawings which illustrate an embodiment of 100 the invention:

Figure 1 is a longitudinal section through 105 the nozzle and part supporting it, enlarged;

Fig. 2 is a similar view, further enlarged, of a detail of Fig. 1;

Fig. 3 is a transverse section of the same on the line 3—3 of Fig. 2, with the shell 31 omitted; and

Fig. 4 is a similar view of a modified 5 form.

Referring to the drawings, 31 indicates a tubular plug having a thread 41 by which it may be screwed tightly into a place provided for it in a tubular base 44", which in 10 turn is adapted in any suitable way to be inserted through the wall of and mounted rigidly within the mixing chamber of an internal combustion engine. As such mounting forms no part of the invention claimed 15 herein it need not be further described except to say that the base 44" provides both the support in the chamber wall and the passage 44' through that wall from the external oil supply system containing a pump. The 20 pump periodically increases the pressure of oil in passage 44', and, positively displacing a certain amount of oil at each stroke, forces it along and into the stem 44 of the valve, and out as hereinafter described. It is con- 25 templated that the base 44" shall be fitted so that the tubular plug 31 which it carries is about in the center of the mixing and combustion passage, with air surrounding it and preferably flowing past it on all sides in the 30 general direction of its own axis. The function of the parts with which the present invention is concerned is to project and distribute oil in all directions about the axis of the passage 44, intermittently and with- 35 out permitting any residual drops to be formed on the outer lip, and without permitting any passage to become clogged. The outer end of tube 31 has a lip or face 42 with a concave conical surface constituting a seat 40 against which fits the convex conical lip or face 43 of the valve 40. This closure shuts off oil completely, although the small grooves 47' remain continuously open as be- 45 low described. The valve 40 has a tubular 50 stem 44 which fits within the tube 31 and centers the valve upon its seat. A spring 45 strung upon this stem, between a nut at its inner end and a shoulder on the interior of the tube 31 tends to hold the faces 42 and 55 43 in contact. The inner end of the stem is open for entrance of oil. Piercing the wall of the stem close to the valve 40 are a few radial holes 46, four being represented, in equidistant locations around the circum- 60 ference. The diameter of passage through the tubular stem is relatively large, large enough so that there is no danger of that passage becoming clogged. The fewness of these holes, 46, leads to the result that if one 65 of them should become somewhat clogged a materially heavier duty would be put upon the others with a resulting increase of resistance, and consequently with material increase of pressure upon the one which is 70 clogged, tending automatically to clear it.

These holes 46 are herein referred to as the primary distribution passages or orifices. Each such passage delivers into an independent cavity 47, outside of the stem 44, and extending somewhat along the circumference. These cavities may be formed by milling a groove in the surface of the tubular stem somewhat as indicated by the dotted lines in Fig. 2, without breaking through much of the face 43 of the valve. 75 From some part of each cavity 47 a small groove 47' leads across the face 43 of the valve. As illustrated in Fig. 2 this is located at the end of the cavity which is remote from the primary orifice 46. As illustrated in the modification shown in Fig. 4 it is located directly opposite the primary orifice 46. In either event it affords a channel which never becomes entirely closed but which really is not large enough for any 80 material flow to occur when the valve is closed. It serves, however, to concentrate the flow at that place when the lips 43 and 42 are almost closed together. It is too small for any flow to occur through it except when the oil is propelled by the pump; is too small to take the volume that flows whenever oil is being propelled, in normal operation. Hence, in normal operation the lips 43 are always spread from the lips 42 85 by the effort of oil to escape, and oil flows out from those two parallel surfaces 42, 43 along the whole length of each cavity 47. There are cavities 47 on all sides, and these 90 cavities may if desired cover a larger portion of the circumference than is represented as being backed by cavities. These arrangements facilitate the accurate and certain distribution of the very small quantity of oil 95 which may be delivered at each stroke. The 100 concentration of the flow in the channels 47' at the beginning of each stroke, and at the end of each stroke produces an evenly balanced distribution about the axis. The 105 holes 46 are of sufficiently small aggregate 110 cross section to make sure that some oil passes through each of them at each discharge. By being few in number they can at the same time be large enough to reduce the danger of any one becoming clogged. 115 Any clogging occurring beyond them will be automatically cleared. The arrangement produces concentration of the oil at a few points, equidistant along the line where distribution is desired, in passing the short 120 distance from the main body to the outside of the stem; and provides distribution outside of the stem by the cavities 47 which extend part way around the stem from each concentration point and permit oil to escape 125 throughout correspondingly large arcs. In so escaping it passes between surfaces which are but slightly separated from each other, and so it acquires a high velocity. As it escapes radially, or at least in the directions of 130

divergent elements of conical surface, it is broken up and spread throughout the air which is at the moment in the vicinity of the nozzle. In the type shown in Fig. 2 the 5 cavities 47 extend somewhat obliquely with respect to the axis of the stem and also obliquely with respect to the primary orifices 46. In the type shown in Fig. 4 they extend symmetrically in both directions from the 10 primary orifice.

The relatively large size of the passage through the tubular stem permits the holding therein of a considerable body of oil very close to the point of discharge. The 15 avoidance of long, small passages reduces the danger of oil in such a passage being carbonized by the excessive heat of the vicinity, and increases the ease with which any such deposits may be cleared. Another feature 20 is the relatively large part of the total flow at each discharge which must pass through any one of the holes; and another feature is the fact that the cavity beyond each orifice is not connected directly with the other 25 cavities, so that it gets the full effect of the thrust every time the pump operates.

I claim as my invention:

1. An atomizing nozzle having an automatically variable discharge opening for intermittent action comprising a tube; a terminal valve having the valve face and valve seat parallel surfaces pressed together in closing; and a valve stem which is tubular, fitting closely within said tube, conveying 30 fluid within the stem to the immediate vicinity of said valve, and having distribution passages leading thence through the wall of the stem directly to the valve seat when the valve is closed.
2. An atomizing nozzle having an automatically variable discharge opening for intermittent action comprising a tube; a terminal valve having the valve face and valve seat parallel surfaces pressed together in closing; and a valve stem which is tubular, fitting closely within said tube, conveying 35 fluid within the stem to the immediate vicinity of said valve, and having distribution passages leading thence through the wall of the stem directly to the valve seat when the valve is closed.
3. An atomizing nozzle having an automatically variable discharge opening for intermittent action comprising a tube; a terminal valve having the valve face and valve seat parallel surfaces pressed together in closing; and a valve stem which is tubular, fitting closely within said tube, conveying 40 fluid within the stem to the immediate vicinity of said valve, and having distribution passages leading thence through the wall of the stem directly to the valve seat when the valve is closed; said tubular stem having its conveying passage large enough not to be clogged by carbonization of fuel therein.
4. An atomizing nozzle having an automatically variable discharge opening for intermittent action comprising a tube; a terminal valve having the valve face and valve seat parallel surfaces pressed together in closing; and a valve stem which is tubular, fitting closely within said tube, conveying 45 fluid within the stem to the immediate vicinity of said valve, and having distribution passages leading thence through the wall of the stem directly to the valve seat when the valve is closed; said tubular stem having its conveying passage large enough not to be clogged by carbonization of fuel therein.
5. An atomizing nozzle having an automatically variable discharge opening for intermittent action comprising a tube; a terminal valve having the valve face and valve seat parallel surfaces pressed together in closing; and a valve stem which is tubular, fitting closely within said tube, conveying 50 fluid within the stem to the immediate vicinity of said valve, and having distribution passages leading thence through the wall of the stem directly to the valve seat when the valve is closed; said tubular stem having its conveying passage large enough not to be clogged by carbonization of fuel therein.
6. An atomizing nozzle having an automatically variable discharge opening for intermittent action comprising a tube; a terminal valve having the valve face and valve seat parallel surfaces pressed together in closing; and a valve stem which is tubular, fitting closely within said tube, conveying 55 fluid within the stem to the immediate vicinity of said valve, and having distribution passages leading thence through the wall of the stem directly to the valve seat when the valve is closed; said tubular stem having its conveying passage large enough not to be clogged by carbonization of fuel therein.
7. An atomizing nozzle having an automatically variable discharge opening adapted for intermittent action with distributed peripheral discharge, comprising a tube; a terminal valve with seat thereon and a stem guided within said tube; there being passages for the fluid to reach the said seat, and continuously open grooves through said seat at intervals around it, whereby distribution begins on all sides of the valve simultaneously; the said valve being adapted to open under pressure of said fluid to permit its flow over relatively large spaces of the valve seat beside said grooves.
8. An atomizing nozzle having an automatically variable discharge opening adapted for intermittent action with distributed peripheral discharge, comprising a tube; a terminal valve with seat thereon and a stem

when the valve is closed; said distribution passages being few in number, whereby the clogging of one would materially reduce the total available area of fluid passages.

4. An atomizing nozzle having an automatically variable discharge opening for intermittent action comprising a tube; a terminal valve; and a valve stem which is tubular, fitting closely within said tube, conveying fluid within the stem to the immediate vicinity of said valve, and having distribution passages leading thence through the wall of the stem directly to the valve seat; there being distribution cavities extending peripherally from the distribution 75 passages, within the valve and bordering on the valve seat.

5. An atomizing nozzle having an automatically variable discharge opening for intermittent action comprising a tube; a terminal valve; and a valve stem which is tubular, fitting closely within said tube, conveying fluid within the stem to the immediate vicinity of said valve, and having distribution passages leading thence through 80 the wall of the stem directly to the valve seat; there being distribution cavities extending peripherally from the distribution passages, within the valve and bordering on the valve seat, said distribution cavities being 85 separate from each other.

6. An atomizing nozzle having an automatically variable discharge opening for intermittent action comprising a tube; a terminal valve; and a valve stem which is tubular, fitting closely within said tube, conveying fluid within the stem to the immediate vicinity of said valve, and having distribution passages leading thence through 90 the wall of the stem directly to the valve seat; there being distribution cavities extending peripherally from the distribution passages, within the valve and bordering on the valve seat, said distribution cavities being 95 separate from each other.

7. An atomizing nozzle having an automatically variable discharge opening adapted for intermittent action with distributed peripheral discharge, comprising a tube; a terminal valve with seat thereon and a stem guided within said tube; there being passages for the fluid to reach the said seat, and continuously open grooves through said seat at intervals around it, whereby distribution begins on all sides of the valve simultaneously; the said valve being adapted to open under pressure of said fluid to permit its flow over relatively large spaces of the valve seat beside said grooves.

8. An atomizing nozzle having an automatically variable discharge opening adapted for intermittent action with distributed peripheral discharge, comprising a tube; a terminal valve with seat thereon and a stem

120

130

guided within said tube; there being passages for the fluid to reach the said seat; distribution cavities bordering said valve seat and separate from each other; and continuously open grooves through said seat at intervals around it, whereby distribution begins on all sides of the valve simultaneously; the said valve being adapted to open under pressure of said fluid to permit its flow over relatively large spaces of the valve seat beside said grooves.

9. An atomizing nozzle having an automatically variable discharge opening for intermittent action comprising a tube; a terminal valve; and a valve stem which is tubular, fitting closely within said tube, conveying fluid within the stem to the immediate vicinity of said valve, and having distribution passages leading thence through the wall of the stem directly to the valve seat; and cavities between the stem and tube, bordering the valve seat and more extensive than their respective distribution passages.

10. An atomizing nozzle having an automatically variable discharge opening adapted for intermittent action with distributed peripheral discharge, comprising a tube; a terminal valve with seat thereon and with face parallel to the seat and pressed against it in closing and a stem guided within said tube; there being passages for the fluid to reach the said seat directly when the valve is closed, adapted to conduct the body of fluid in relatively large cross section close to said valve seat, and thence by short distribution passages of relatively small cross section.

11. An atomizing nozzle having an automatically variable discharge opening adapted for intermittent action, comprising a tube; a terminal valve having the valve face and valve seat parallel surfaces pressed to-

gether in closing; there being a passage within the tube conveying fluid to the immediate vicinity of said valve and large enough not to be clogged by carbonization of fuel therein, and distribution passages leading thence through a wall directly to the valve seat, when the valve is closed.

12. An atomizing nozzle having an automatically variable discharge opening adapted for intermittent action, comprising a tube; a terminal valve; there being a passage within the tube conveying fluid to the immediate vicinity of said valve and large enough not to be clogged by carbonization of fuel therein, and distribution passages leading thence through a wall to the valve; and leading thence through a wall to the valve; seat and extending peripherally from the distribution passages.

13. An atomizing nozzle having an automatically variable discharge opening adapted for intermittent action, comprising a tube; a terminal valve; there being a passage within the tube conveying fluid to the immediate vicinity of said valve and large enough not to be clogged by carbonization of fuel therein, and distribution passages leading thence through a wall to the valve; and distribution cavities bordering on the valve seat and extending peripherally from the distribution passages; and fine grooves leading from the distribution cavities, the valve faces closing tight together except at said grooves.

Signed by me at Boston, Mass., this 4th ⁷⁵ day of August, 1916.
